UNITED STATES PATENT OFFICE.

JOSEPH E. J. GOODLETT, OF MEMPHIS, TENNESSEE.

AUTOMATIC CAN-FILLING MACHINE.

SPECIFICATION forming part of Letters Patent No. 660,101, dated October 23, 1900.

Application filed August 19, 1899. Serial No. 727,781. (No model.)

To all whom it may concern:

Be it known that I, JOSEPH E. J. GOODLETT, a citizen of the United States, residing at Memphis, in the county of Shelby and State 5 of Tennessee, have invented certain new and useful Improvements in Automatic Can-Filling Machines; and I do hereby declare the following to be a full, clear, and exact description of the invention, such as will enable others skilled in the art to which it appertains to make and use the same.

An especial object of this invention is to provide for filling and capping cans whose caps are frictionally held when forced into 15 sealing position; but in general the object is to provide a simple, convenient, and effective machine for filling cans of any size automatically and in endless succession. The machine acts only while held in operation by the 20 positive act of the operator, and hence it stops whenever the operator is for any reason of the opinion that stopping is desirable.

In the accompanying drawings, Figure 1 is a side elevation of the machine. Fig. 2 is a 25 section on the line 2 2, Fig. 1, looking in the direction of the arrow. Fig. 3 is an elevation showing part of the machine as seen from the left in Fig. 1. Fig. 4 is a plan view. Figs. 5 and 6 are respectively a vertical and a horizontal section of certain filling devices. Fig. 30 7 is a plan view of certain can-holding devices. Fig. 8 is a plan view of drip-catching devices. Fig. 9 is a section at 9 9, Fig. 8.

In the figures, A designates a suitable frame; 35 B, a power-shaft mounted therein; C, a cam-shaft driven from the power-shaft by gears C' C², and D⁰ an endless-belt traveling table consisting of sprocket-chains D, connected by slightly-separated bars D' and carried by 40 sprocket-wheels D², mounted upon shafts D³, parallel to the shafts B C. Centrally above the table are can-filling devices E, and at some distance to one side of the filling devices and nearly over that end of the table 45 toward which the upper folds of the chains move are cap-seating devices F. The table has a step-by-step movement, and the cans placed upon it at the end opposite the cap-seating devices advance and stop beneath the 50 filling devices. When filled, they advance one step and rest during the filling of the next

succeeding set of cans, and during the interval of rest the caps are placed upon them. The next advance carries them beneath the cap-seating devices F, where during an interval of rest the caps are pressed home. The various movements just mentioned are produced by the cam-shaft C, upon the free tapered ends of which are placed cams C³, which, acting through antifriction-rollers C⁴ in the usual manner, drive vertical rods C⁵ at each side of the machine. At the top of the machine these rods are attached to a cross-head C⁶, which slides vertically upon guide-rods C⁷, fixed to the frame A, and near their lower ends they are slotted to fit over the shaft C, which thus prevents their lateral displacement. To the middle portion of one rod is attached by a common slot-and-pivot connection C⁸ one arm C⁸ of a bell-crank lever pivoted to the frame and having its other arm C⁹ connected by a link C¹⁰ to a rack-bar C¹¹, which engages a loose gear C¹² upon one of the sprocket-wheel shafts. The gear bears spring-actuated pawls C¹³, which engage a ratchet-wheel C¹⁴, with which the sprocket-wheel shaft is rigidly connected. Now, the gear being revoluble independently of the sprocket-wheel, the pawls force the latter to rotate when the rack-bar moves in one direction, but slip upon the ratchet-wheel and leave the sprocket-wheel at rest when the rack-bar and gear move in the contrary direction, and thus the table receives a step-by-step movement. Cleats D⁴ are fixed to the table at suitable intervals, and the cans to be filled are placed upon the table in advance of the cleats at the opposite end to the cap-seating device in position so as to rest laterally in depressions D⁵ in a cross-bar D⁶. When cans are thus in position, the advance of the table causes them to be engaged by one of the cleats and carried forward, and the proportions of travel are such that at the end of one of the table's steps they lie immediately beneath the filling devices.

To compensate for any wear or stretching of the chains, or either of them, one of the sprocket-wheel shafts is mounted in brackets D⁷, which are adjusted upon the frame A by means of screws D⁸ and are rigidly locked in adjustment by bolts D⁹. Adjustment of the

cross-bar D⁶ is also provided for, it being fixed to arms D¹⁰, pivoted upon the brackets and locked in position by set-screws D¹¹.

For filling the cans cylinders G are fixed in the frame above the table in such manner that they may be readily removed in case of necessity, and each is provided with a long closely-fitting plunger G', carried by the cross-head C⁶. Each cylinder has two openings below—an inlet G^X and an outlet G^{XX}—opened and closed alternately by a spring-pressed conical valve G², whose stem passes through a stuffing-box G⁰. The valve G² is formed with a through-port g and a right-angle port g'. The outlet G^{XX} connects with the through-port g to a filling or discharge spout G³, while the inlet G^X, by way of the right-angle port g', communicates with a feed-channel G⁴, leading to a chamber G⁵, into which the material is brought by a pipe G⁶. To insure quick and certain filling of each cylinder, each is provided with an opening G⁷, forming a free passage leading from a point just below the highest position of the lower end of the plunger to the corresponding channel G⁴ or chamber G⁵. The rotary valves G² are operated by a properly-timed cam H upon the shaft C, the cam acting through a roller H', pivoted lever H², rod H³, bell-crank lever H⁴, connecting-bar H⁵, and crank-arms H⁶, fixed to the valve-stems, respectively.

Immediately below the filling-spouts G³ is a drip-catching device consisting of a reciprocating bar I, bearing a pan I', having in its bottom elongated openings I², surrounded by flanges I³. The bar is connected by a link I⁴ to one arm of the bell-crank lever H⁴, so that as the latter swings to open the valves it slides the bar longitudinally and brings the opening I² into register with the corresponding spouts, and thus allows the material to pass down into the cans below. As the valves close this movement is reversed and any material that may escape passes along the pan, around the flanged openings, and through a spout I⁴ to a receptacle I⁵, whence it is withdrawn through an outlet I⁶. One set of cans being thus filled, the next advance of the table brings another set into position for filling and leaves the former set between the filling and cap-seating devices. Here the caps are added by the operator, and a moment later the table again advances, bringing the cans just provided with caps beneath the devices at F. These devices include a cross-head J, moving vertically in ways in the frame members J' and bearing downwardly-projecting elastic pressers J², which force the caps home when the cross-head descends. The cross-head is drawn downward by rods J³, pivotally attached to bent levers J⁴, which swing about pivots J⁵ and bear at their free ends short arms J⁶, hinged to swing upward but not downward with reference to the levers and yieldingly held at their outermost or, with reference to the levers, lowest positions by springs J⁷.

These arms lie in the path of upwardly-round-ed adjustable projections K upon the rods C⁵, and as the rods rise the projections push the arms aside and pass them; but when the rods descend the projections catch the arms and swing the levers downward until the arms in moving in a circular path about the lever-pivots pass out of the path of the projections. Obviously this swinging of the levers draws the cross-head down in its ways, and thus forces the pressers upon the caps in the manner already suggested. The instant after the arms escape from the projections all these parts are restored to normal positions by the force of stout springs K' beneath the cross-head. At the next advance of the table the cans just capped are delivered upon their sides upon a transversely-inclined platform L, along which when cylindrical they roll to other devices (not shown) for labeling, &c.

Throughout their whole course upon the table the cans are guided by light bars M, attached to the frame of the cap-seating devices and extending to the opposite end of the machine.

To hold the cans during the filling and to insure having each pushed back against the cleat which advances it, I fix to the frame a rigid bar N, from which depend adjustable rods N', bearing at their lower ends can-clasping springs N², between which the cans are forced by the cleats. The springs, which are arranged in coacting pairs, are curved inward and outward centrally and inward and outward at their ends, so that each can is held with some firmness in exact position between the springs of a pair while the table is at rest and the cans are being filled; but as the table again advances the cleat just behind the cans imparts a positive forward movement, the springs yield, and the cans pass out of their embrace between their yielding outward-projecting ends.

The form of the cams operating the plungers is such that the latter descend to a predetermined point before the opening of the valves, and thus some part of the material which has entered the cylinders is suddenly forced out through the two openings G^X and G⁷ in each cylinder, through one or both of which it may have entered, and hence if either opening be clogged the difficulty is overcome before any harm results.

The gear C' upon the driving-shaft is free from the shaft, but is forced to rotate therewith when desired by means of a friction-clutch one member O of which is rigidly attached to gear, while the other member O' slides without rotation upon the shaft. The second member is moved into and out of engagement with the first by a centrally-pivoted lever O², itself swung upon its pivot by a centrally-pivoted bent lever O³, normally held in one position by a spring O⁴, which yieldingly resists depression of the outer end of the lever by the foot. The arrangement is

such that the clutch engages only while the outer end of the bent lever is held down by the operator, or, in other words, the machine operates only while the operator by positive action compels it to operate.

The machine may be adapted for use with cans of various sizes, the only change required being the substitution of cams upon the free ends of the cam-shaft, and with the construction shown such substitution may be made with trifling loss of time.

It is evident that changes may be made in the forms shown without passing the limits of my invention and that certain subcombinations may be used in machines otherwise materially different from that herein illustrated. I do not therefore wish to limit myself to the precise devices set forth, but desire to cover all the patentable novelty disclosed.

What I claim is—

1. A cylinder for a can-filling machine constructed with an inlet and an outlet at its lower end, a channel having a discharge-spout and extending beneath the inlet and outlet, and a valve, for opening and closing the inlet and the outlet, alternately, having a right-angle port providing communication between the inlet and the channel, and also a through-port providing communication between the outlet and the discharge-spout.

2. A cylinder for a can-filling machine constructed with an inlet and an outlet at its lower end, a chamber near its upper end, a channel having a discharge-spout and extending from the chamber and beneath the inlet and outlet, an opening providing communication between the cylinder and the chamber, and a valve located in the channel and controlling the inlet, the outlet, and the discharge-spout.

3. A cylinder for a can-filling machine constructed with an inlet and an outlet at its lower end, a chamber near its upper end, a channel having a discharge-spout and extending from the chamber and beneath the inlet and outlet, an opening providing communication between the cylinder and the chamber, and a valve, for opening and closing the inlet and the outlet alternately, having a port providing communication between the inlet and the channel, and also a port providing communication between the outlet and the discharge-spout.

4. A can-filling machine comprising a cylinder constructed with an inlet and an outlet at its lower end, a channel having a discharge-spout, a valve controlling the discharge-spout, a long closely-fitting plunger working in the cylinder, vertical guide-rods, a cross-head, by which the plunger is carried, sliding on the guide-rods, vertical rods, to which the cross-head is attached, having slotted lower ends, a cam-shaft extending through the slotted lower ends of the vertical rods, and cams secured to the cam-shaft and connected

with the lower ends of the vertical rods for driving the latter.

5. A can-filling machine comprising a cylinder constructed with an inlet and an outlet at its lower end, a channel having a discharge-spout, a valve controlling the discharge-spout, a crank-arm secured to the valve-stem, a valve-rod pivoted to the crank-arm, a drive-rod, a bell-crank lever connecting the valve-rod with the drive-rod, a pivoted lever with which the drive-rod is connected, a cam-shaft, and a cam-wheel secured to the cam-shaft and connected with the pivoted lever.

6. A can-filling machine comprising a cylinder constructed with a discharge-spout, a valve controlling the discharge-spout, a reciprocating bar, a drip-pan secured to the bar, and having an elongated opening in its bottom, a flange surrounding the opening, and a discharge-spout, a receptacle having an outlet, and means for operating the valve and bar, alternately.

7. A can-filling machine comprising a cylinder constructed with a discharge-spout, a valve controlling the discharge-spout, a valve-arm secured to the valve-stem, a valve-rod pivoted to the crank-arm, a drive-rod, a bell-crank lever, connecting the valve-rod with the drive-rod, a pivoted lever with which the drive-rod is connected, a cam-shaft, a cam-wheel secured to the cam-shaft and connected with the pivoted lever, a reciprocating bar, a drip-pan secured to the bar, and having an elongated opening in its bottom, a flange surrounding the opening, and a discharge-spout, and a link connecting the bar with the bell-crank lever.

8. A can-filling machine comprising a table provided with means to engage the cans placed thereon and force them to advance therewith, means for imparting a step-by-step movement to the table, a rigid bar located over the table, adjustable rods depending from the bar and the clasping-springs secured to the rods in pairs and curved inward and outward centrally, and inward and outward at their ends.

9. A can-filling machine comprising an endless-belt table having cleats for advancing the cans, an inclined cross-bar having depressions in which the cans rest, brackets having adjustable arms on which the cross-bar is supported, and means for advancing the table with the cans in series, step by step.

10. A can-filling machine comprising an endless belt having cleats for advancing the cans, an inclined cross-bar having depressions in which the cans rest, and the guide-bars between which the cans pass extending from end to end of the machine.

In testimony whereof I affix my signature in presence of two witnesses.

JOSEPH E. J. GOODLETT.
